Specification for Design.

Patented Dec. 18, 1917.

Application filed October 15, 1917. Serial No. 196,762. Term of patent 14 years.

To all whom it may concern:

Be it known that I, LEO D. JACOBY, a citizen of the United States, residing at Winthrop, in the county of Suffolk and State of Massachusetts, have invented a new and original and ornamental Design for Paper Spoons, of which the following is a specification, reference being had to the accompanying drawings, forming a part thereof.

In the drawings, Figure 1 is a plan view, Fig. 2 is a side elevation, Fig. 3 is a longitudinal section of a spoon embodying my new design, and Figs. 4 and 5 are sections on lines 4—4, and 5—5 of Fig. 1, respectively.

What I claim is:

The ornamental design for a paper spoon as shown.

LEO D. JACOBY.
